Attorney

UNITED STATES PATENT OFFICE.

GEORGE GILLESPIE, OF ANN ARBOR, MICHIGAN.

EXTENSION-MICROMETER.

1,388,034.

Specification of Letters Patent.

Patented Aug. 16, 1921.

Application filed October 7, 1919. Serial No. 328,990.

To all whom it may concern:

Be it known that I, GEORGE GILLESPIE, a citizen of the United States, residing at Ann Arbor, in the county of Washtenaw and State of Michigan, have invented certain new and useful Improvements in Extension-Micrometers, of which the following is a specification.

This invention relates to improvements in micrometers and has for its primary object to provide an instrument of this character embodying novel features of construction whereby the position of the gage pin carrying jaws may be varied to adapt the micrometer for use in connection with work having a wide variance in size.

Another object is the provision of a micrometer of this character embodying such means as will afford and reliably maintain the relative adjustment of the jaws.

With these and other objects in view as will appear as the description proceeds the invention comprises the novel features of construction, combination of elements and arrangement of parts which will be more fully described in the following specification and set forth with particularity in the claims appended hereto.

Figure 1 represents a side elevation of the improved micrometer.

Fig. 2 represents a bottom plan view thereof.

Fig. 3 represents a transverse sectional view through the shanks of the jaws taken on the line 3-3 of Fig. 1.

Fig. 4 represents a fragmentary perspective view of one terminal of one of the jaw shanks, and

Fig. 5 represents a perspective view, partly broken away, of the terminal of the other jaw.

Referring to the drawing in detail, where in similar reference numerals designate corresponding parts throughout the several views, the numerals 5 and 6 indicate the opposed curved jaws of the improved micrometer which are provided with terminal extensions 7 and 8, respectively, receiving the relatively stationary and adjustable gage pins 9 and 10. As in the usual construction of micrometers the relatively adjustable pin 10 is provided with an approved type of adjusting device designated generally by the numeral 11 which is adequately mounted upon the jaw 6.

The companion jaws 5 and 6 are provided

with elongated flat shanks 12 and 13, respectively, which are arranged in superposed relation and are adapted for relative adjustment, as will hereinafter appear.

The shanks 12 and 13 are provided with registering longitudinal slots 14 receiving the shank portions 15 of retaining screws the headed terminals 16 of which are disposed oppositely and engaged with the opposed shanks 12 and 13 adjacent the opposite ends thereof. The terminals of the two shanks opposite the heads are provided with screw threads and thumb nuts 17 are threaded upon these terminals of the screws and gaskets 18 are interposed between the thumb nuts and jaw shanks.

The inner surface of the jaw shank 12 is formed with a series of uniformly spaced and transversely extending recesses 19 for receiving a series of transversely extending ribs or projections 21 carried by the shank 13 whereby the jaw shanks and jaws are rigidly locked in adjusted position. Upon proper adjustment of the thumb nuts 17 the projections or ribs 21 may be withdrawn from the recesses 19 and the shanks 12 and 13 adjusted relatively to obtain the desired adjustment of the jaws 5 and 6 and the gage pins 9 and 10, the fine adjustment of the pin 10, as will be understood, being secured by proper adjustment of the device 11. To further insure proper movement of the shanks 12 and 13 and prevent relative lateral movement thereof which might affect the adjustment of the pins 9 and 10, a guide rib or projection 22 is formed upon the inner edge of the shank 13, or that longitudinal edge disposed adjacent the jaws 5 and 6. The other shank 12 is formed with a longitudinal recess 23 receiving the rib 22 and thus insuring proper relation of the jaw shanks.

What I claim is:

1. In a micrometer, a pair of relatively adjustable companion jaws, gage pins carried thereby, said jaws being provided with adjustably related shanks, and interlocking means carried by the shanks to lock the latter in adjusted position when assembled.

2. In a micrometer, a pair of companion jaws, formed with shank portions, interlocking means carried by the shanks to lock the latter in adjusted position when assembled, and means to releasably secure the shanks in assembled relation.

3. In a micrometer, a pair of companion

- jaws, superposed shanks formed on said jaws, one of the shanks having a series of uniformly spaced recesses, transverse ribs carried by the other shank engaging said recesses, said ribs being arranged to prevent relative movement of the shanks in the direction of their adjustment, and means for clamping the shanks together to maintain the ribs in position in the recesses.
- 10 4. A micrometer comprising a pair of companion jaws, shanks formed on said jaws and adapted for relative adjustment, a series of equidistant transverse ribs carried by one of the shanks arranged in angular relation to the direction of adjustment of the jaws, the other shank having a series of recesses adapted to receive said ribs, said shanks having longitudinal registering slots therein, means movably engaged through said slots for clamping the shanks together and maintaining the ribs in position in the recesses.
- 15 5. A micrometer comprising a pair of companion jaws, shanks formed on said jaws disposed in superposed relation, transverse ribs carried by one shank, arranged in angular relation to the direction of adjustment of the jaws, the other shank being provided with recesses adapted to receive said ribs to

rigidly lock the shanks against movement 30 along the line of adjustment of the jaws, said shanks having longitudinal registering slots therein, screws slidably engaged in said slots, and means coacting with said screws to draw the shanks together and maintain 35 the latter in relatively adjusted position.

6. A micrometer comprising a pair of companion jaws, shanks formed on said jaws, means for securing the shanks in adjusted position, one of the shanks having 40 longitudinal and transverse grooves therein, and transverse ribs formed on the other shank engaged in said grooves to maintain the shanks in alinement.

7. A micrometer comprising a pair of companion jaws, shanks carried by said jaws, transverse ribs carried by one shank, the other shank having a series of transverse recesses receiving said ribs, the recessed shank having a longitudinal groove therein, a longitudinal guide rib carried by the ribbed shank engaging in said groove to maintain the shanks in alinement, and means to clamp the shanks together to maintain the latter in adjusted position.

In testimony whereof, I affix my signature hereto.

GEORGE GILLESPIE.
